United States Patent Office

Des. 196,307
Patented Sept. 17, 1963

196,307

SPOOL

Robert F. Vance, 2144 E. 26th St., Tulsa, Okla.

Filed Aug. 6, 1962, Ser. No. 71,187

Term of patent 14 years

(Cl. D41—1)

FIGURE 1 is a perspective view of a spool embodying my new design;

FIGURE 2 is an elevational view thereof;

FIGURE 3 is a cross-sectional view thereof taken on the line 3—3 of FIGURE 2; and

FIGURE 4 is an end elevational view thereof.

I claim:

The ornamental design for a spool, as shown.
